HOOD ORNAMENT FOR AUTOMOBILES OR THE LIKE

George W. Walker, Bloomfield Hills, Mich., assignor to Ford Motor Company, Dearborn, Mich., a corporation of Delaware

Filed Nov. 25, 1960, Ser. No. 62,968

Term of patent 7 years

(Cl. D14—18)

FIG. 1 is a side elevational view of a hood ornament for automobiles or the like, showing my new design;

FIG. 2 is a top plan view;

FIG. 3 is a front view; and

FIGS. 4, 5, 6 and 7 are sectional views taken on the planes indicated by the lines 4—4, 5—5, 6—6 and 7—7 of FIG. 1.

I claim:

The ornamental design for a hood ornament for automobiles or the like, substantially as shown.
